US00D930933S

(12) **United States Design Patent** (10) **Patent No.:** **US D930,933 S**
(45) **Date of Patent:** **** Sep. 14, 2021**

(54) **TRASH CAN**

- (71) Applicant: **simplehuman, LLC**, Torrance, CA (US)
- (72) Inventors: **Frank Yang**, Rancho Palos Verdes, CA (US); **Di-Fong Chang**, Torrance, CA (US); **Myk Lum**, Irvine, CA (US); **Adam Wade**, Rancho Santa Margarita, CA (US); **Helen Miller**, Diamond Bar, CA (US)
- (73) Assignee: **simplehuman, LLC**, Torrance, CA (US)
- (**) Term: **15 Years**
- (21) Appl. No.: **29/778,497**
- (22) Filed: **Apr. 13, 2021**

Related U.S. Application Data

- (60) Continuation of application No. 16/284,996, filed on Feb. 25, 2019, which is a division of application No. (Continued)
- (51) **LOC (13) Cl.** **09-09**
- (52) **U.S. Cl.** **USPC D34/9**
- (58) **Field of Classification Search**
USPC D34/1, 7, 8, 9, 10, 11

(57) **CLAIM**

The ornamental design for a trash can, as shown and described.

DESCRIPTION

FIG. 1 illustrates a front top perspective view of a trash can. FIG. 2 illustrates a rear top perspective view of the trash can of FIG. 1.

FIG. 3 illustrates a rear bottom perspective view of the trash can of FIG. 1.

FIG. 4 illustrates a front view of the trash can of FIG. 1.

FIG. 5 illustrates a left side view of the trash can of FIG. 1, the right side view being a mirror image of the left side view.

FIG. 6 illustrates a rear view of the trash can of FIG. 1.

FIG. 7 illustrates a top view of the trash can of FIG. 1; and,

FIG. 8 illustrates a bottom view of the trash can of FIG. 1.

The broken lines shown in the figures are included for the purpose of illustrating unclaimed portions of the trash can and form no part of the claimed design.

1 Claim, 8 Drawing Sheets
